UNITED STATES PATENT OFFICE

LOUIS GOLDSTEIN, OF UNION CITY, NEW JERSEY

DESIGN FOR A TEXTILE FABRIC

Application filed August 28, 1929. Serial No. 32,572. Term of patent 3½ years.

To all whom it may concern:

Be it known that I, LOUIS GOLDSTEIN, a citizen of the United States, and residing at #519 30th Street, Union City, county of Hudson, and State of New Jersey, have invented a new, original, and ornamental Design for Textile Fabric, of which the following is a specification, reference being had to the accompanying drawing, forming part thereof.

The accompanying drawing shows a piece of textile fabric embodying my design.

I claim:

The ornamental design for a textile fabric as shown in the accompanying drawing.

LOUIS GOLDSTEIN.
